Primary Examiner — Selina Sikder(74) *Attorney, Agent, or Firm* — Fitch, Even, Tabin & Flannery LLP(57) **CLAIM**

We claim the ornamental design for a transmitter, as shown and described.

DESCRIPTION

FIGS. 1-7 are perspective, left side elevation, right side elevation, top, bottom, front elevation and rear elevation views, respectively, of transmitter in accordance with a first embodiment of our new design; and,

FIGS. 8-14 are perspective, left side elevation, right side elevation, top, bottom, front elevation and rear elevation views, respectively, of transmitter in accordance with a second embodiment of our new design.

In the drawings, the broken lines depict portions of the transmitter that form no part of the claimed design.
